[57] ABSTRACT

A pneumatic apparatus for firing an automatic firing weapon comprising a cylinder which can be impinged by a compressed air source, actuation of the cylinder being controlled by a first valve. There is provided a second valve which is open in its starting position, and upon actuating the first valve the second valve can be closed for interrupting the delivery of air to the cylinder.

6 Claims, 1 Drawing Figure

PNEUMATIC APPARATUS FOR FIRING AN AUTOMATIC FIRING WEAPON

BACKGROUND OF THE INVENTION

The present invention relates to a new and improved construction of pneumatic apparatus for firing an automatic firing weapon and is of the type incorporating a cylinder which can be impinged with air by means of a compressed air source, actuation of the cylinder being controlled by a first valve.

According to a known construction of apparatus of this type triggering of an automatic firing weapon takes place by means of a piston of a cylinder arranged directly at the weapon, the cylinder being pneumatically actuated by remote control. A drawback of this system is that cessation of firing does not occur automatically, rather must be undertaken by the operating personnel.

SUMMARY OF THE INVENTION

Hence, it is a primary object of the present invention to provide an improved construction of pneumatic apparatus for firing an automatic firing weapon which is not associated with the aforementioned limitations of the state-of-the-art proposals.

Another and more specific object of the present invention relates to a new and improved construction of pneumatic apparatus for firing an automatic weapon wherein after a certain time — for instance after a single shot or for the limiting as a function of time of rapid or series firing — there can be automatically stopped the firing operation.

Now in order to implement these and still further objects of the invention, which will become more readily apparent as the description proceeds, the invention contemplates that there is provided a second valve which is open in its starting position and this second valve is closed upon actuating the aforesaid first valve for the purpose of interrupting the delivery of air to the cylinder.

BRIEF DESCRIPTION OF THE DRAWING

The invention will be better understood and objects other than those set forth above, will become apparent when consideration is given to the following detailed description thereof. Such description makes reference to the annexed drawing wherein the single FIGURE of the drawing schematically illustrates an exemplary embodiment of pneumatic apparatus for firing an automatic firing weapon.

DETAILED DESCRIPTION OF THE PREFERRED EMBODIMENTS

Describing now the invention it is to be understood that only enough of the structure of the apparatus has been shown in the drawing to simplify the illustration thereof and to enable those skilled in the art to readily understand the underlying concepts of this development. Turning therefore more specifically to the single FIGURE of the drawing it will be recognized that there is shown a trigger or actuation mechanism which incorporates two actuation pistons 1 and 2 which in any suitable and therefore not particularly illustrated manner are supported at the firing triggers or the like of a respective cannon. The actuation pistons 1 and 2 are each located in a respective cylinder 3 and 4. The cylinders 3 and 4 are subdivided by the pistons 1 and 2 into two respective compartments or chambers 5, 7 and 6,

8 respectively. The effective or work surfaces 9 and 10 of the pistons 1 and 2 which bound the compartments 5 and 6 respectively of the cylinders 3 and 4 are larger than the effective or work surfaces 11 and 12 of the actuation pistons 1 and 2 which bound the compartments 7 and 8. These compartments 7 and 8 are coupled with compressed air sources 13 and 14 respectively. In the other compartments 5 and 6 of the cylinders 3 and 4 there open the conduits or lines 15 and 16 which lead to the slide valves 21 and 22.

Depending upon the position of the slide valves 21 and 22 the conduits 15 and 16 are either connected with the respective compressed air sources 23 and 24 or vent to the atmosphere.

For the purpose of adjusting the slide valves 21 and 22 compressed air is delivered from the conduits or lines 27 and 28, and which overcomes the force of a respective spring 25 and 26. The conduits 27 and 28 are connected via the respective slide valves 29 and 30 with the conduit 31. Each slide valve 29 and 30 forms a feeler which under the force of the springs 47 and 48 bears against the cartridge belt and is displaced in the event that the relevant cartridge belt is at its end i.e. depleted. Conduit 27 or 28 is then vented to the atmosphere via the slide valves 29 and 30.

The conduit 31 opens into a slide valve 34 defining a reversing or switching valve and can be connected by means of such slide valve 34 either with a conduit 41 or conduit 37. For adjusting or shifting the slide valve 34 compressed air is delivered from the conduit 61 and which must overcome the force of a spring 35. By means of the conduit 41 the slide valve 34 is connected with the elements which serve to trigger series firing or to trigger a limited series firing. In this regard one is concerned with the slide valves 39 and 40 and furthermore — for triggering the limited series firing — a slide valve 43 by means of which a conduit or line 42 can be either connected with the atmosphere or with a compressed air source 45. The compressed air arriving from the conduit 42 at the slide valve 39 overcomes the force of a spring 38 and displaces the slide valve 39. For adjusting the slide valve 43 compressed air is delivered from the conduit 46 and from a flask or container 52, defining a delay element, and which compressed air must overcome the force of a spring 44. For triggering the limited series firing there is furthermore provided a slide valve 50 which can interrupt a conduit 51. Conduit 51 is connected on the one hand via a throttle 69, defining a delay element, with a conduit 55, on the other hand it leads to the flask or container 52. By means of a check valve 54 it is connected with a conduit 53 which opens into the conduit 41. The conduit 55, into which open the conduits 41 and 51, leads to a foot actuation slide valve 80 which is equipped with a connection to the atmosphere, a connection to a compressed air source 79 and a spring 81. The slide valve 34 is furthermore connected with the elements for triggering an individual shot and for triggering a number of individual shots. Here one is concerned with the slide valve 60 by means of which the conduit 61 is either vented to the atmosphere or can be connected with the conduit 55.

The conduit 37 connects the slide valve 34 with a slide valve 36. This slide valve 36 possesses a connection to a compressed air source 67, an opening 36a to the atmosphere as well as crosswise connecting channels 36b for connecting the compressed air source 67

with a conduit 71 and the conduit 37 with the atmosphere upon actuating the slide valve 36 by means of the compressed air emanating from a conduit 20. In the conduit 20 the compressed air is delivered via a double check valve 19 from conduits 17 and 18. The conduit 17 opens into the conduit 15 at the first cylinder 3. The conduit 18 opens into the conduit 16 at the second cylinder 4. For adjusting the slide valve 36 there cannot be present for the compressed air from the conduit 20 any counter force generated by compressed air from a conduit 66. The conduit 66 can be connected via a slide valve 63 either with a compressed air source 64 or with a further conduit 62. For adjusting the slide valve 63 there is delivered compressed air from a conduit 78 and which must overcome the force of a spring 65. The conduit 78 is connected via a slide valve 75 either with the atmosphere, as schematically indicated at 75a, or with a compressed air source 76. For adjusting the slide valve 75 there is delivered compressed air from a conduit 73 and a flask or container 72, and which must overcome the force of a spring 77. The flask or container 72, defining a delay element, is connected via a check valve 74 with a conduit 71. This conduit 71 is connected via the slide valve 36 either to vent into the atmosphere or with the compressed air source 67 and via a throttle 68, defining a delay element, with a slide valve 70. By means of the slide valve 70 it is possible to interrupt the conduit 71. Furthermore, the flask or container 72 is connected with the conduit 71.

All of the described compressed air sources are connected to a common compressed air container. Instead of employing the described slide valves or slides it would be possible to use other suitable valves.

The slide valves 40, 50, 60 and 70, each of which define a respective adjustment element, can be operated by a common adjustment switch or control switch which has not been particularly illustrated in the drawing to preserve clarity in illustration. This adjustment switch has five positions for five adjustment possibilities of the pneumatic trigger mechanism, namely:

- Position 1 :Safety position
- Position 2 :Single shot
- Position 3 :Series firing with low cadence
- Position 4 :Limited series firing
- Position 5 :Series firing with normal cadence of the weapon.

The mode of operation of the described apparatus is as follows: if the adjustment switch is placed into position 1, then the slide valves 40, 60 are vented, the connected conduits 41, 61 and the slide valves 50, 70 interrupt the connected conduits 51, 71. Upon operating the foot actuation slide valve 80 no shots are fired.

If the adjustment switch is brought into position 2 for triggering or firing an individual shot, then the slide valves 50, 70 interrupt the connected conduits 51, 71 and the slide valve 40 vents the conduits 41. The slide valve 60 on the other hand is located in a position in which upon operating the foot actuation slide valve 80 compressed air flows from the compressed air source 79 via the conduit 55 through the conduit 61. Consequently, the slide valve 34 is displaced against the force of the spring 35 and the conduit 31 is connected with the conduit 37 leading to the slide valve 36. From the compressed air source 67 compressed air flows through conduits 37 and 31 via the slide valves 29 and 30 into the conduits 27 and 28. The slide valves 21 and 22 are

displaced against the force of the springs 25 and 26 and the conduits 15 and 16 are connected with the compressed air sources 23 and 24. The compartments or chambers 5 and 6 fill-up and the actuation pistons 1 and 2 are impinged. A respective shot is fired. From the conduits 15 and 16 compressed air flows through the conduits 17 and 18 via the check valve 19 through the conduit 20 to the slide valve 36. Since, however, in position 2 of the adjustment switch compressed air flows from the source 79 also through the conduit 56, the slide valve 57 is actuated against the action of the spring 58 and there is interrupted delivery of compressed air from the source 59 via the conduit 62, the slide valve 63 and the conduit 66 to the slide valve 36. Thus, there is not effective any counterpressure or counter force to the pressure from the conduit 20 at the slide valve 36, such is actuated and the infeed of compressed air from the compressed air source 67 to the pistons 1 and 2 is interrupted. The conduit or line 37 is vented via the slide valve 36, the compressed air which flows from the source 67 into the conduit 71 does not cause anything to happen, since the conduit 71 is interrupted by the slide valve 70. The air pressure from the compressed air sources 13 and 14 displace the actuation pistons 1 and 2 back into their starting position and the process is terminated. There is fired a respective individual shot.

If the adjustment switch is brought into position 3, then the slide valve 50 interrupts the conduit 51 and the slide valve 40 vents the conduit 41, on the other hand, the slide valves 60 and 70 are in a position in which the connected conduits 61 and 71 are continuous, i.e. not interrupted. Upon operating the foot actuated slide valve 80 there flows, analogous to the processes which occurred during the above described position 2, compressed air from the compressed air source 67 up to the pistons 1 and 2. The compressed air flowing through the conduit 56 again interrupts the infeed of compressed air from the compressed air source 59 to the slide valve 36. The compressed air which flows through the conduit 20 to the slide valve 36 again does not experience any counter force from the conduit 66 and the slide valve 36 is displaced. The air from the compressed air source 67 flows through the conduit 71. Now however the slide valve 70 is in the position in which the compressed air arriving via the throttle 68 reaches the region of the container 72 and such begins to fill. If the pressure in the container 72 and the conduit 73 is sufficiently large, then the force of the spring 77 of the slide valve 75 is overcome and the conduit 78 is connected to the compressed air source 76. This compressed air brings about displacement of the slide valve 63 against the force of the spring 65 and compressed air again flows to the slide valve 36, this time from the source 64 via the slide valve 63 and the conduit 66. The slide valve 36 is again displaced back and compressed air flows from the compressed air source 67 via conduit 37 and the slide valve 34, again in the already described manner, to the actuation pistons 1 and 2. A further shot is fired. The entire procedure can repeat for such length of time as the slide valve 80 is actuated. After each shot the flask or container 72 is vented to the atmosphere via the check valve 74 and the conduit 71.

If the adjustment switch is brought into position 4, for triggering limited series firing, then the slide valve 70 interrupts the connected conduit 71 and via the slide

valve 60 the connected conduit 61 is vented to the atmosphere. The slide valves 50 and 40 are in a position in which upon actuating the foot actuated slide valve 80 compressed air flows from the compressed air source 79 via the conduit 55 into the conduit 41 and via the throttle 69 to the conduit 51. By means of the conduit 41 compressed air arrives via the slide valves 39 and 34 at the conduit 31, from which location it flows further via the slide valves 29 and 30 through the conduits 27 and 28 and the slide valves 21 and 22 are actuated against the force of the springs 25 and 26. Compressed air arrives from the compressed air sources 23 and 24 through the agency of the conduits 15 and 16 to the actuation pistons 1 and 2. The compressed air which flows via the valve 19 through the conduit 20 does not bring about any interruption of the infeed of air. The slide valve 36 is displaced by the compressed air from the conduit 20 since the compressed air from the conduit 66 escapes to the atmosphere via the slide valve 57. This slide valve 57 is displaced by the air flowing out of the conduit 56. Displacement of the slide valve 36 does not have any effect, since the compressed air flowing up to the pistons 1 and 2 in this case does not emanate from the source 67, rather from the compressed air source 79. Throttled compressed air which flows via the conduit 51 is stored in the flask or container 52 and upon attaining a sufficient pressure such, via the conduit 46, brings about a displacement of the slide valve 43 against the force of the spring 44. Compressed air flows from the source 45 through the conduit 42 and displaces the slide valve 39 against the force of the spring 38. The conduit 41 is interrupted and the series firing is terminated. The duration of series firing is governed by the filling of the flask or container 52 via the throttle 69. With more pronounced throttling interruption of the series firing occurs at a later time. The flask or container 52 is vented to the atmosphere via the valve 54 and the conduit 53, as soon as the foot actuation slide valve 80 is no longer actuated.

With the adjustment switch in position 5, for triggering series firing, the slide valve 60 vents the connected conduit 61 and the slide valves 70 and 50 interrupt the conduits 71 and 51. The slide valve 40 is in a position in which upon actuating the foot actuation slide valve 80 compressed air continuously flows from the compressed air source 79 through the conduits 55 and 41. Analogous to the position 4 of the adjustment switch there occurs series firing. Since, however, the slide valve 50 interrupts the conduit 51 the series firing is not limited via the slide valves 43 and 39, rather is continuously carried out as long as the foot actuated slide 80 is operated or as long as the slide valves 29 and 30 re-

main open.

For all five positions of the switch the slide valves 29, 30 monitor the associated cartridge belt and interrupt the connected conduits 27, 28 in the event that the cartridge belt is depleted. Consequently, the infeed of air to the relevant actuation piston 1 or 2 is interrupted.

The valve 19 prevents, upon disconnecting one of the actuation pistons 1 or 2 by one of the slide valves, 29 and 30, that also the conduit 15 or 16, which leads to the other actuation piston 1 or 2, will be vented. The actuation pistons 1 and 2 can function independently of one another in the event one of them is disconnected by the slide valve 29 or 30.

While there is shown and described present preferred embodiments of the invention, it is to be distinctly understood that the invention is not limited thereto, but may be otherwise variously embodied and practiced within the scope of the following claims. ACCORDINGLY,

20 What is claimed is:

1. A pneumatic apparatus for firing an automatic firing weapon, comprising a cylinder which can be impinged with air from a compressed air source, a first valve for controlling actuation of said cylinder, a second valve which is open in its starting position, said second valve being closed upon actuating said first valve in order to interrupt the infeed of air to said cylinder.

2. The pneumatic apparatus as defined in claim 1, further including a third valve and delay elements for returning the second valve back into its starting position, said third valve being closed in its starting position and being actuated via the second valve through the agency of said delay elements.

3. The pneumatic apparatus as defined in claim 1, wherein said cylinder can be connected via the first valve with the compressed air source.

4. The pneumatic apparatus as defined in claim 3, further including a fourth valve which is normally open, a fifth valve for closing the fourth valve for interrupting the infeed of air to the cylinder, said fifth valve being actuated via delay elements.

5. The pneumatic apparatus as defined in claim 3, further including a reversing valve for selectively delivering compressed air to the cylinder from the second valve or from the fourth valve.

6. The pneumatic apparatus as defined in claim 5, wherein a respective adjustment element is associated with the reversing valve, the third valve, the fourth valve and the fifth valve, for selectively actuating the reversing valve, or the reversing valve and the third valve, or the fourth valve and the fifth valve, or for interrupting the delivery of air to the fourth valve.
